UNITED STATES PATENT OFFICE.

EDWARD W. BURT, OF PHILADELPHIA, PENNSYLVANIA, AND HENRY S. CHAPIN, OF HEMPSTEAD, NEW YORK, ASSIGNEES TO S. L. ALLEN AND COMPANY, OF PHILADELPHIA, PENNSYLVANIA, A COPARTNERSHIP.

CARDBOARD SLED.

No. 853,624.

Specification of Letters Patent.

Patented May 14, 1907.

Application filed January 24, 1906. Serial No. 297,571.

To all whom it may concern:

Be it known that we, EDWARD W. BURT, a citizen of the United States, and a resident of the city of Philadelphia, State of Pennsylvania, and HENRY S. CHAPIN, a citizen of the 5 United States, and a resident of the town of Hempstead, State of New York, have jointly invented certain new and useful Improvements in Cardboard Sleds, of which the following is a full, clear, and complete disclosure.

Our invention relates to advertising devices, particularly to that class of devices where the advertisement is represented on 15 the reverse side of a blank, the said blank being of such a configuration that it is adapted to be bent up into miniature articles of manufacture, and to have the various detailed parts represented in design on the face of the 20 blank.

Our invention consists in the features of construction and manner of operation set forth in the following specification and accompanying drawing, in which like reference 25 characters refer to corresponding parts.

In the drawings:—Figure 1 is a plan view of a blank, having attached thereto a further detail of our invention; Fig. 2 is a longitudinal section taken on line 2—2 of Fig. 1; Fig. 3 is a transverse section taken on line 3—3 of Fig. 1; and Fig. 4 is a transverse section taken on line 4—4 of Fig. 1; Fig. 5 is a plan view of the blank having its side edges bent downwardly to form the runners; Fig. 6 is a 35 elevation of Fig. 5; Fig. 7 is a similar view to Fig. 5, but showing the forward ends of the runners swung laterally, and Fig. 8 is a side elevation of Fig. 7.

The blank illustrated in Figs. 1 to 4 inclusive of the drawing is adapted to be that of a miniature sled, and it consists of the middle portion or platform 5, adjacent to which are the side portions or runners 6—6, both of which project forwardly beyond the middle portion, and are connected together by a cross bar 7. (See Fig. 3.) The forward edges of these side portions 6—6 may be curved toward each other, as shown at 10—10. The forward and rear ends of the middle portion 5 may be curved as shown at 13—14, and the rear ends of the side portions may project outwardly and rearwardly, as at 12—12.

From the junction between the middle portion 13 and the side portions 12—12 respectively the blank may be weakened or scored in a straight line to the junction of the outer corners of the forward middle portion with the side portions respectively. This scored or weakened portion is for the purpose of more readily enabling the side portions 6—6 to be bent downwardly at an angle with the middle portion, to form the runners of the sled. On the face of the blank may be represented the design of the braces, clips, rims and other constituent parts of the sled. The forward junction of the side portions with the middle portion may be slit or separated, as shown at 15—15, to allow a greater lateral movement to the forward ends of the runners, when the same are turned down at an angle with the sled. On the top of the blank we pivotally attach a T-shaped piece 16. The said T is pivoted to the middle portion by the eyelet 8 and to the cross bar by the eyelet 9. On the reverse side of the blank may be printed such advertisements as may be desired. When the side portions 6—6 are turned down to form runners for the sled the middle portion 5 will serve as a platform, and the forward portions of said runners, by virtue of their resiliency, may be swung laterally by means of the T-shaped lever 16 as shown in Figs. 7 and 8. The slits 15—15, which separate the runners from the platform at its forward portion permit a greater swing to the lateral motion of the runners. In operating the sled to give the said lateral movement to the runners, the T-shaped lever is manipulated on an arc having the pivot 8 as its center, and by virtue of its connection with the cross bar 7 at the pivot 9 communicates a lateral motion to said cross bar, which in turn swings the runners.

We have described the above blank as one being adapted to be bent up into a sled, but our invention is not necessarily confined to blanks for this character of article of manufacture as we may utilize other blanks adapted to be bent up into other articles of manufacture, provided such is suggested by the disclosure of this blank. Neither is our invention limited to the peculiar structure of the sled herein described. The same principle may be employed in designing a blank

for any other structure of sled. The blanks are usually made out of cardboard, but may be made out of any other light sheet material, according to the taste or use to which 5 it is desired to employ the same.

The representation on the front of the blank is merely for the purpose of illustrating other details of construction which are not embodied in the configuration of the blank 10 itself, and may be accompanied by fanciful designs or illustrations, as is the custom on other advertising devices. The scored or weakened portions are not necessarily included in the structure of the blank, as the 15 article may be bent up without such, especially if constructed to have the bend occur through a short length of the blank. This short length may be affected by the curvature and configuration of the front and rear 20 ends of the platform or middle portions and the rear ends of the side portions or runners. Although the use of the lever 16 adds greatly to the attractiveness of the blank for the purpose described, yet the presence of the same 25 is not essential, as the function of swinging the runners laterally may be performed by hand. The blanks may be complete for the purpose described without being bent up into an article of manufacture, and may be 30 distributed for commercial use as a blank alone.

What we claim and desire to secure by Letters Patent is:

1. As an advertising device, a resilient 35 blank for a sled, comprising a platform portion embraced between a pair of runner portions, the said runner portions projecting beyond the forward end of said platform portion, and the said blank having its shortest 40 longitudinal dimensions along the junction between the runner and platform portions and also being split longitudinally to separate the runner portions from the forward end of said platform portion to permit the 45 runners to swing laterally when the blank is bent up to form a sled.

2. As an advertising device, a resilient blank for a sled, comprising a platform portion embraced between a pair of runner portions, the said runner portions projecting beyond the forward end of said platform portion, and the said blank having its shortest 50 longitudinal dimensions along the junction between the runner and platform portions and also being split longitudinally to separate the runner portions from the forward end of said platform portion to permit the runners to swing laterally when the blank is bent up to form a sled, and a cross bar connecting 55 the forward ends of said runner portions.

3. As an advertising device, a blank consisting of a middle portion, two side portions projecting beyond one end of said middle portion, the said portions having their outer 60 edges curved inwardly toward their projected

ends, and a cross bar connecting said ends, in combination with a flat piece pivoted to said middle portion and to said cross bar.

4. As an advertising device, a blank consisting of a middle portion, two side portions projecting beyond one end of said middle portion, the said side portions having their outer edges curved inwardly toward their projected ends, and a cross bar connecting said ends, in combination with a flat **T**-shaped lever pivoted at its foot to said middle portion and at its head to said cross bar. 70 75

5. As an advertising device, a blank for a sled consisting of a middle portion, two side portions and a cross bar, the two side portions having their outer edges parallel but curved inwardly toward each other at their forward ends, the said ends being connected by said cross bar, in combination with means engaging said middle portion and said cross 80 85 bar and adapted to swing laterally the side portions when the same are turned at an angle with the middle portion.

6. As an advertising device, a blank consisting of a middle portion, two side portions projecting beyond one end of the said middle portions, the said side portions having their outer edges curved inwardly toward their projected ends, and a cross bar connecting said ends, in combination with means engaging said middle portion and said cross bar, and adapted to swing laterally the side portions when the same are turned at an angle with the middle portion. 90 95

7. As an advertising device, a blank for a sled consisting of a middle portion, side portions and cross bar, the side portions extending beyond the forward end of the middle portion, and having their outer ends connected by a cross bar, in combination with means engaging said middle portion and said cross bar, and adapted to swing laterally the side portions when the same are turned at an angle with the middle portion. 100 105

8. As an advertising device, a sled bent up out of sheet material and consisting of a platform and two runners bent downwardly at each side respectively of said platform, the end portions of said runners being resilient and connected by a cross bar beyond the end 110 115 of said middle portion, the forward portions of said runners being adapted to yield laterally.

9. As an advertising device, a sled bent up out of sheet material consisting of a platform 12 and two runners bent downwardly at each side respectively of the platform, the said runners being separated from and projecting beyond the forward end of said platform and adapted to yield laterally, said separated portions being resilient.

10. As an advertising device, a sled bent up out of sheet material and consisting of a platform and two runners bent downwardly at each side respectively of said platform,

the end portions of said runners being resilient and connected by a cross bar beyond the end of said middle portion, the forward portions of said runners being adapted to yield laterally in combination with means for swinging said runners laterally.

11. As an advertising device, a sled bent up out of sheet material and consisting of a platform and two runners bent downwardly at each side respectively of said platform, the end portions of said runners being resilient and connected by a cross bar beyond the end of said middle portion, the forward portions of said runners being adapted to yield laterally in combination with means pivoted to the platform for swinging the runners laterally.

12. As an advertising device, a sled bent up out of resilient sheet material and consist-

ing of a platform and two runners bent downwardly at each side respectively of said platform, the end portions of said runners being resilient and connected by a cross bar beyond the end of said middle portion, the forward portions of said runners being adapted to yield laterally in combination with means for swinging the runners laterally, the said means consisting of a T-shaped lever pivoted at its foot to the platform and at its head to the cross bar.

In witness whereof we have hereunto set our hands this 13 day of January, 1906.

EDWARD W. BURT. [L. S.]
HENRY S. CHAPIN. [L. S.]
